UNITED STATES PATENT OFFICE.

LANDON P. SMITH, OF NEW YORK, N. Y.

DESIGN FOR A MEMBER FOR PAIRS OF PLIERS.

SPECIFICATION forming part of Design No. 30,237, dated February 21, 1899.

Application filed May 26, 1898. Serial No. 681,845. Term of patent 14 years.

To all whom it may concern:

Be it known that I, LANDON P. SMITH, a citizen of the United States, residing in the city of New York, in the county and State of New York, have invented and produced a new and original Design for a Member of a Pair of Pliers, of which the following is a specification, reference being had to the accompanying drawings, forming a part thereof.

10 The leading feature of my design relates to the peculiar configuration of the jaw of the plier member, the configuration consisting in the rounded corners of the outer face of the jaw.

15 In the accompanying drawings, Figure 1 is

a perspective view of a plier member embodying my novel design, and Fig. 2 is a cross-section thereof on line 2 2 of Fig. 1.

The jaw portion A of the plier member is formed on its outer face, throughout the 20 length of said jaw, with rounded corners B and C.

I claim—

The design for a member of a pair of pliers herein shown and described.

LANDON P. SMITH.

In presence of—

MARY MANTEL,
J. F. HEMENWAY.
